TIME-INDICATING FACE FOR A HOROLOGE

Shigeru Fukumoto, Nishinomiya, Japan, assignor to
Kabushiki Kaisha Suncrux Research Office, Kobe,
Japan

Filed Oct. 13, 1971, Ser. No. 189,062

Claims priority, application Japan Apr. 15, 1971

Term of patent 14 years

Int. Cl. D10—07

U.S. Cl. D42—1 B

Fig. 1

Fig. 2

Fig. 3

FIG. 1 is a front elevational view of a time-indicating face for a horologe showing my new design;

FIG. 2 is a right side elevational view thereof; the left side being identical;

FIG. 3 is a plan view thereof.

The drawings are shaded for color contrast.

I claim:

The ornamental design for time-indicating face for a horologe, as shown and described.
